UNITED STATES PATENT OFFICE.

DAVID L. MURCHEY, OF DETROIT, MICHIGAN.

DESIGN FOR A CASE FOR GAME COUNTERS OR REGISTERS.

52,670.

Specification for Design.

Patented Nov. 12, 1918.

Application filed January 18, 1918. Serial No. 212,532. Term of patent 14 years.

To all whom it may concern:

Be it known that I, DAVID L. MURCHEY, a citizen of the United States, residing at Detroit, in the county of Wayne and State of Michigan, have invented a certain new, original, and ornamental Design for a Case for Game Counters or Registers, of which the following is a specification, reference being had to the accompanying drawing, forming a part thereof.

Figure 1 is a plan view of the obverse side of a case embodying my design. Fig. 2 is a plan view of the reverse side of the case. Fig. 3 is an edge elevation of the case.

I claim:

The ornamental design for a case for game counters or registers as shown.

DAVID L. MURCHEY.
